INDICATION LIGHT

Joseph Henry Schellman, Ridley Park, and William Robert Law, Havertown, Pa., assignors to Hetherington, Inc., Sharon Hill, Pa., a corporation of Delaware

Application July 14, 1954, Serial No. 443,404

5 Claims. (Cl. 340—252)

The present invention relates to indicator lights of 15 character employed in connection with electric circuits especially on aircraft.

A purpose of the invention is to increase the light transmitted from an indicator light by providing a reflector at the end of the barrel which engages the transparent cover.

A further purpose is to displace the lamp so that its light-giving portion is all between the reflector and the 20 end of the transparent cover remote from the barrel.

A further purpose is to simplify and improve the construction of the test switch in an indicator light so that 25 difficulty will not be encountered by twisting of the parts and so that contact will be made more reliable in both the normal position and the test position.

Figure 1 is a side elevation of an indicator light and 30 switch combination in accordance with the invention.

Figure 2 is a rear elevation.

Figure 3 is an exploded side elevation partly in axial 35 section showing the lamp and indicator cover and barrel to enlarged scale.

Figure 4 is an enlarged axial section taken on the line —4 of Figure 2 showing the test switch in open position.

Figure 5 is an exploded perspective of the indicator 40 light and test switch combination of the invention.

Figure 6 is an axial section showing a variation in which the indicator light assembly is employed without 45 a test switch.

Indicator lights are extensively used where electrical controls are employed, particularly on aircraft, to show that circuits are closed. These devices frequently are provided with test switches so that on pushing the light can be connected to a test circuit to test the bulb and 50 desirably to indicate the operativeness of other circuit connections.

Difficulty has been encountered in the prior art in 55 number of respects. Many of the test lights have not even sufficient illumination so that it was necessary to use excessively high candle powers.

In the present invention a small but very efficient reflector has been placed on the end of the barrel to project a maximum of light into the area of vision. Furthermore the cover and barrel assembly has been redesigned so that the light-giving portion of the bulb is located toward the observer with respect to the reflector.

In certain of the prior art constructions it has been difficult to replace the bulb and has been necessary to engage the contact by pliers. In the present device, the engagement on the bulb is carried out beyond the diameter of the barrel so that the bulb can readily be pulled out and grasped by the fingers.

In prior art devices the switch construction has been complicated and expensive and has given trouble through unreliability of contacts. In the present invention the device has been simplified and made more reliable, and

2

provision has been made to prevent twisting of the switch contact or of the barrel.

Considering now the drawings in detail, particularly with respect to Figures 1 to 5 inclusive, the instrument board 20 is provided with an opening 21 through which the tubular housing 22 of the indicator light passes. The housing has a flange 23 at its outer end which engages on the front of the instrument board and is threaded rearwardly at 24, receiving a washer 25 and nut 26 at the back of the instrument board 20 to hold the indicator light in place by engagement with the thread 24.

The housing is tubular and hollow and has near its forward end engaging the inside of an inwardly directed flange 23' a tubular insulating cup 27 which at suitably diametrically opposite positions is longitudinally inferiorly ribbed toward the rear at 27', as later discussed. The cup 27 at the rear has a disc-like bottom 28 having a central longitudinal opening 29, and a longitudinal opening 30 at one side through which passes the tab 31 of a fixed metallic contact 32 extending over the side of the bottom 28 toward the forward end. The contact 32 has a central opening 33 in line with the opening 29 in the bottom and a notch 34 which engages around one of the ribs 27' and prevents the contact 32 from turning.

Rearward of the insulating cup 27 and fitting the inside of the housing is a tubular insulating sleeve 35 which extends to near the rearward end of the housing, at which point the housing receives an insulating disc 36 engaging the insides thereof and held by crimping of the rear of the housing at 37.

On the side of the disc-like bottom 28 toward the disc 36 is placed a central normal lighting switch contact 38 which has an interior opening 40 in line with openings 29 and 33, and the contact 38 has a rearwardly extending tab 41 which narrows at 41' to form a shoulder 42 and passes through an opening 43 in insulating washer 36, thus holding the contact in position by the engagement of the shoulder 42 against the insulating washer. The washer 36 also has an opening 44 which passes the tab 31 of the contact 32.

Inside the washer 36 at the center is located a transverse portion of a switch fixed contact 45 which has a central opening 46 and is held by rivet 47 passing through a central hole in the disc 36. A tab 48 from this contact passes through an opening 49 in the disc 36 and is visible at the rear of the indicator light.

Inside the insulating cup 27 and slidable with respect to it is a forwardly extending tubular casing 50 which is internally threaded at one end and receives externally threaded portion 52 of barrel 51. The barrel is preferably reduced in diameter at both sides of the threaded portion 52.

At the forward end of the barrel it is preferably enlarged and forms a reverse conical reflector surface 53 which may be used as machined, but it is desirably ground or otherwise smoothed for maximum effectiveness, and is preferably of a metal which forms a good mirror surface such as nickel plated brass. The barrel at its forward end is joined suitably by molding to a transparent cover 54 around the enlarged portion 53' of the barrel and in direct contact with the reflector surface 53. The plastic cover may be embedded in recesses on the outside of the barrel, not shown. The cover is suitably of a transparent plastic such as cellulose acetate-butylate, methyl methacrylate, or polystyrene. The interior of the dome of the cover 54 desirably conforms closely with the curve of the dome of the illuminating portion of electric light bulb 55 so that the bulb fits snugly in the hollow of the cover and its illuminating portion is desirably all forward of the rearward edge of the

60

65

70

75

80

85

90

reflector 53. The socket portion 56 of the bulb extends through the barrel and at the rearward end the bulb has an enlarged flange 57 which sticks out slightly at 58 beyond the outside of the barrel so that the bulb can be grasped by the fingers. The bulb makes one contact to 55 the barrel around its metallic socket portion 56; and has a second contact 59 at the center of the rear portion as well known.

The casing 50 has at diametrically opposite positions 10 longitudinal rearwardly extending slots 60 which preferably align with the ribs 27 in the insulating cup 27.

At the center of the assembly rearwardly of the lamp is placed a contact button 62 which engages the center contact 59 on the lamp, and is desirably of rivet form, as shown, being riveted over at 63 on the rearward side, 15 of an insulating disc 64 and forming a spring socket 65 on the side of the contact button remote from the lamp. The insulating disc 64 engages the inside of the casing 50 and is slidable with respect thereto to compensate for slight differences in the position of the central contact 20 58 of the lamp, and the disc has ears 66 which extend out into and are slidable in the slots 60 of the casing.

Positioned rearwardly of the insulating disc 64 is an insulating sleeve 67 which seats in the rear of the casing 50 and is held by spinning over the rear of casing 50 at 25 67. The sleeve is held against a shoulder 67' in the casing. The sleeve 67 supports a movable contact extension 68 which has a spring socket 69 at its forward end and is flanged over beyond the sleeve 67 to engage the sleeve at 70. The sleeve 67 extends around the 30 outside of the spring socket at 71. The movable switch contact extension 68 extends rearwardly and in guiding relation with the opening 29 at the center of disc-like bottom 28 and at its rearward end is surrounded by contact washer 72 which is secured and held on the extension 68 by riveting at 73. Thus in one position of the movable switch contact extension the washer 72 engages the contact 38 and in the other position it engages the 35 rivet 47.

Surrounding and in spaced relation to the switch contact extension 68 is placed a contact spring 74 of helical compression type which at one end engages contact 32 and at the other end engages the rear of casing 50.

Placed between spring sockets 65 and 69 is a helical compression spring 75.

In operation of the device of Figures 1 to 5, the light will light normally by current flowing through contact 38, washer 72, movable switch contact extension 68, spring 75 and contact button 62 to the center contact of the lamp and then from the outside of the lamp through barrel 51, casing 50, contact spring 74 and contact 32. Light from the illuminating portion of the bulb which passes out laterally in part strikes the reflector 53 and is reflected forward.

When it is desired to test, the operator pushes in on the cover 54, which moves the movable switch contact extension to disconnect from contact 38 and connect to rivet 47 which illuminates the bulb on a test circuit; which also includes the contact 32.

On release of the pressure on the cover 54, the assembly returns to the position for normal lighting as shown in Figure 4.

In order to replace a bulb it is merely necessary to unscrew the cover and barrel assembly from the casing, grasp the bulb on the flange 57, take out the old bulb and put in a new bulb. When the cover-barrel assembly is screwed back into the casing, if the bulb is slightly longer, this is compensated for by compression of spring 75.

Also when the cover is pushed inwardly to test, the test contacts are closed before the rear of the cover engages the flange on the housing and overtravel is permitted by compression of spring 75, thus assuring good contacts in the test position.

The device can be used with indicator lights which

lack the test switch. Thus in Figure 6, the same cover, barrel and lamp assembly is placed in a housing 78 which is externally supported like the housing 22, and is internally threaded at 78' to engage the outside of the barrel. In this form an insulating disc 64' is slidable inside the housing and supports the contact button 62 as already described. The rearward portion of the housing has a shoulder 80 and is enlarged to receive an insulating disc 67' which engages a contact element 68' which in this case is fixed and riveted to the disc but otherwise resembles the extension 68. The rear of the housing is spun over at 37 to hold disc 67'. The spring 75 allows for differences in length of the lamp.

One of the requirements is that the cover 54 must stand an axial force of 200 pounds, and this is possible due to the advantageous dome-shaped form of the cover and the excellent support which it is given.

Having thus described our invention what we claim as new and desire to secure by Letters Patent is:

1. In an indicator light, a dome-shaped transparent cover having a hollow interior, a tubular barrel joined to the cover at the open end and having a reverse conical end on the barrel adjoining the cover, an electric light bulb extending through the barrel into the hollow of the cover and having its light-giving portion located substantially between the reverse conical face of the barrel and the opposite end of the cover, the electric light bulb having a flange beyond the end of the barrel remote from the cover, extending out to a diameter greater than the barrel, and a tubular casing surrounding the flange of the electric light bulb and surrounding and interthreaded with the barrel.

2. In an indicator light, a tubular housing, a switch contact at one end of the housing, a tubular casing inside the housing and reciprocable with respect thereto, a tubular barrel threaded within the casing, a transparent cover on the end of the barrel remote from the casing, an electric lamp within the barrel and cover, a fixed contact within the housing intermediate between the ends and having a central opening, an electrically conducting spring between the fixed contact and the casing, and a switch extension interconnected with the lamp at one end and extending through the opening and in one position of the casing engaging the switch contact.

3. In an indicator light, a tubular housing, a metallic casing in spaced relation to the housing insulated therefrom, and movable longitudinally thereof, a barrel threaded into the casing, a transparent dome-shaped hollow cover on the end of the barrel remote from the casing, a lamp within the barrel and casing, an insulating mounting disc secured to the casing rearwardly of the lamp and slidably longitudinally of the casing, a contact button in the insulating disc engaging the central contact on the lamp and having a socket disposed oppositely to the lamp, a fixed contact mounted inside the housing between the rear of the housing and the casing, insulated from the housing and having a central opening, a contact spring extending from the fixed contact to the end of the casing remote from the lamp, an insulating element inside the casing between the first insulating disc and the fixed contact, first and second opposed switch contacts at the rear of the housing and insulated therefrom, a contact extension extending from the insulating element through the opening at the center of the fixed contact and in one position of the casing engaging the first switch contact, the contact extension having a socket on the end disposed toward the lamp and an overtravel spring extending between the contact button and the contact extension and fitting into the sockets, the contact extension in another position engaging the second switch contact.

4. In an indicator light, a tubular housing, a first insulating element inside the housing at one end thereof, a metallic casing in insulated spaced relation to the housing and movable longitudinally thereof, a barrel threaded into the casing, a transparent dome-shaped hollow cover

on the end of the barrel remote from the casing, a lamp within the barrel and casing, an insulating mounting disc secured to the casing rearwardly of the lamp and slideable longitudinally of the casing, there being a longitudinal slot in the casing extending from the insulating disc to the end of the casing remote from the cover and there being ears on the insulating disc extending into the longitudinal slots, a contact button at the center of the insulating mounting disc engaging the central contact on the lamp and having a spring socket on the end remote from the lamp, a fixed contact inside and in spaced relation from the housing intermediate between the two ends and having a central longitudinal opening, a contact spring between the fixed contact and the end of the casing remote from the cover, a second insulating element secured to the rear of the casing, there being longitudinally slideable interlocks between the first insulating element and the casing in line with the slots on the casing, opposed switch fixed contacts in the rear of the housing insulated therefrom, a movable contact mounted at the center of the second insulating element and extending from the second insulating element toward the nearer switch contact and in the retracted position of the housing engaging the nearer switch contact, the movable contact having a spring socket disposed on the side toward the lamp, an

5

10

15

20

25

overtravel spring occupying the spring sockets between the contact button and the movable contact, and the movable contact in rearward position engaging the more remote switch contact.

5. In an indicator light, a dome-shaped transparent plastic cover having a hollow interior, a tubular barrel having an interior diameter generally in alignment with the hollow interior of the plastic cover, having an annular reverse conical surface on its end adjoining the cover, and joined to the cover over the reverse conical surface and over the outside of the barrel, and an electric light bulb inside the barrel and the hollow of the cover, engaging the interior of the barrel and having its light-giving portion between the reverse conical surface of the barrel and the end of the cover remote from the barrel, the reverse conical surface acting as a reflector for the bulb.
